CASE FOR MILK CONTAINERS OR THE LIKE

Rudolph H. Matthias and Robert L. Beesley, Saginaw,
Mich., assignors to The Dow Chemical Company, Mid-
land, Mich., a corporation of Michigan

Filed Apr. 27, 1964, Ser. No. 79,701

Term of patent 14 years

(Cl. D58—5)

Fig. 2

Fig. 1

Fig. 3

Fig. 4

FIGURE 1 is a side elevational view of a case for milk containers or the like, showing our new design;

FIGURE 2 is a top plan view thereof;

FIGURE 3 is a bottom plan view thereof; and

FIGURE 4 is an enlarged fragmentary cross-sectional view thereof taken along line 4—4 of FIGURE 1.

The dominant features of our design reside in the portion shown in full lines. The sides not shown are the same as that illustrated.

We claim:

The ornamental design for a case for milk containers or the like, substantially as shown and described.
